[57] CLAIM

The ornamental design for a combined auxiliary light and cover therefor, as shown and described.

DESCRIPTION

FIG. 1 is an exploded front perspective view of the combined auxiliary light and cover therefor showing my new design;

FIG. 2 is a rear perspective view thereof with the cover omitted for purposes of disclosure;

FIG. 3 is a side elevational view thereof with the cover omitted for purposes of disclosure;

FIG. 4 is a top plan view thereof with the cover omitted for purposes of disclosure;

FIG. 5 is a front perspective view of the auxiliary light and cover in assembled condition;

FIG. 6 is a front elevational view thereof on an enlarged scale with the cover omitted for purposes of disclosure; and

FIG. 7 is a back elevational view thereof on an enlarged scale with the cover omitted for purposes of disclosure.

FIG. 1

FIG. 2
